UNITED STATES PATENT OFFICE.

JOHN A. HAGERSTROM, OF SCRANTON, PENNSYLVANIA, ASSIGNOR TO VICTOR TYPE-WRITER COMPANY, OF SCRANTON, PENNSYLVANIA, A CORPORATION OF NEW YORK.

MAIN-SHAFT DRIVE.

1,352,124.

Specification of Letters Patent.

Patented Sept. 7, 1920.

Application filed September 29, 1917. Serial No. 194,079.

To all whom it may concern:

Be it known that I, JOHN A. HAGERSTROM, a citizen of the United States, residing at Scranton, in the county of Lackawanna and State of Pennsylvania, have invented certain new and useful Improvements in Main-Shaft Drives, of which the following is a specification.

This invention relates to typewriters and has for its primary object to provide driving connections of improved construction for transmitting power from the main spring or motor to the main ribbon shaft. One of the objects of my invention is to provide improved reversible driving connections between a spring motor and the main ribbon shaft. Other and further objects will appear in the specification and be pointed out in the appended claims, reference being had to the accompanying drawings which exemplify my invention in a preferred embodiment.

In the drawings,—

Figure 1 is a front elevation of a typewriter motor provided with its driving connection and constructed in accordance with the principles of the present invention;

Fig. 2 is a top plan view of the same;

Fig. 3 is a fragmentary detail of the joint between one of the arms or fingers carried by the main spring housing and the drum.

Referring more particularly to the drawings, a bracket 1 is provided with flanges 2 and 3, by means of which it may be connected up to the typewriter frame. Journaled in the frame or bracket 1, is a main spring shaft 4. Journaled on the main spring shaft is a drum 5 provided with a notch 6, within which a screw 7 secures the end of a belt or strap 8, by means of which the carriage is caused to travel along its guide when the escapement mechanism (not shown on the drawings) is in operation. A main spring housing 9 which also turns freely on the main spring shaft 4, is releasably connected to the drum 5 so as to partake of its rotary movement. Within the housing 9 is disposed a main spring 10, one end of said spring being secured to the main spring shaft 4, while the other end 11 of said main spring is secured to said housing, preferably by having a loop 11 formed therein to slip over one of the arms or fingers 12 which are deflected rearwardly and pass through holes or openings

13 in the rear plate of the drum 5. As shown in Fig. 3, each arm or finger 12 makes a bayonet joint with the back wall of the drum 5, said arm being provided with a notch 14 for this purpose. From this description, it will be seen that after the drum 5 and main spring housing 9 have been coaxially arranged on the main spring shaft 4, the loop 11 of the main spring having been passed over one of the arms or fingers 12, said drum and housing may be moved toward each other in an axial direction, causing the arms or fingers 12 to pass through the slots or openings 13, after which a relative angular movement between 60 said drum and housing causes the bayonet joint to become engaged on all of said fingers 12. As shown in the left hand portion of Fig. 1, a key arm or finger 15 is adapted to be passed through a slot 16, which is provided with an outwardly extending recess 17 which permits the key arm 15 to expand radially and so become locked against the adjacent wall of the drum 5, and thus preventing a releasing angular movement of 65 the housing on the drum 5. Freely journaled on the main spring shaft 4 in front of the main spring housing 9, is a crown wheel 18 provided on its outer periphery with a ratchet 19. Coöoperating with the 70 ratchet 19 is a pawl 20, which is journaled on a pin 21, carried by a radial lug 22. The pawl 20 is provided with an arm 23 to which is attached one end of a spring 24, the other end of said spring being connected 75 to a lug 25, carried by the housing 9. A suitable dog 26 is pivotally mounted at 27 upon the frame or bracket 1 and is adapted to lock the crown wheel 18 against retrograde movement. The dog 26 is also provided with an inwardly and forwardly extending guard arm 28, terminating in a rearwardly presented end 29 which extends under the crown or flange 18 of the 80 crown gear and prevents the dog 26 from being displaced more than a small angular movement. A main ribbon shaft 30 which is reciprocable axially, has keyed thereto a spur gear 31 which has a peripheral face portion of greater extent than the axial 85 movement of said shaft 30. By means of this construction, the gear 31 is adapted to remain in mesh with the crown gear 18 at all times during the reciprocatory movement of the main ribbon shaft 30 which 90

takes place in changing the direction of the feed movement of the ribbon.

I claim:

1. In a typewriter, a main spring shaft, a crown wheel journaled on said shaft, a main ribbon shaft, and a gear on said main ribbon shaft and meshing with the crown wheel on said main spring shaft, and a dog having ratchet engagement with said crown wheel, said dog being provided with a guard arm adapted to engage said crown wheel for limiting the displacement of said dog with respect to said crown wheel.
2. In a typewriter, a main spring shaft, a crown wheel, provided with forwardly presented gear teeth and with peripheral ratchet teeth, a dog coöperating with said ratchet teeth, said dog being provided with a guard arm extending around said gear teeth and under the flange of said crown wheel, and a ribbon drive shaft provided with a gear meshing with said gear teeth on the crown wheel.

3. In a typewriter, a main spring shaft, a crown wheel journaled thereon, a main spring for driving said crown wheel, a main ribbon drive shaft arranged transversely to said main spring shaft and reciprocable endwise with respect thereto, and a spur gear keyed to said main ribbon drive shaft and continuously meshing with said crown wheel, said spur gear having teeth elongated lengthwise of said main ribbon drive shaft to adapt it to remain in mesh with said crown wheel during the combined rotary and reciprocatory movements of said main ribbon drive shaft and whereby the contacting portions of said crown wheel and spur gear change during the combined rotary and reciprocatory movements of said main ribbon shaft.

JOHN A. HAGERSTROM.
